JAMES E. BIRDSALL, OF PHILADELPHIA, PENNSYLVANIA.

MUSICAL CABINET.

1,247,785.

Specification of Letters Patent. Patented Nov. 27, 1917.

Application filed December 22, 1915. Serial No. 68,282.

To all whom it may concern:

Be it known that I, JAMES E. BIRDSALL, a citizen of the United States, residing at No. 166 N. Farson street, Philadelphia, in the county of Philadelphia and State of Pennsylvania, have invented a new and useful Improvement in Musical Cabinets, of which the following is a specification.

My invention relates to cabinets for the 10 keeping of so-called music "records" used in connection with mechanical musical instruments and has for its objects to provide a safe and dust-proof housing therefor and to afford a simple means of exposing the contents thereof at a convenient height for making 15 selections so as to obviate the necessity on the part of the user of stooping or assuming any inconvenient or uncomfortable position.

20 The prevailing form of furniture for storing records, etc., is a low, stationary cabinet, frequently used also as a table for the instrument, in which the compartments or shelves continue almost to the floor of the room. This construction compels the user, 25 in making a selection, to assume a stooping, kneeling, or other equally awkward and uncomfortable attitude and, frequently in a place where the light is poorest, whereby the 30 use of the cabinet is more onerous than agreeable. My device overcomes this unpleasant incident by providing means for automatically elevating the contents of the cabinet where the light is best and presenting 35 the records for easy and accessible selection.

For the purpose of illustrating my invention I have shown and described one form 40 thereof which is at present preferred by me, although it is to be understood that the various instrumentalities of which my invention consists can be variously arranged and organized and that my invention is not to be limited to the precise form, arrangement 45 and organization herein shown and described.

The nature, novel characteristic features and scope of my invention will be more fully understood from the following description 50 taken in connection with the accompanying drawings forming part hereof and in which:

Figure 1 is a front elevation of the entire invention, with the front of the cabinet removed showing interior construction; Fig. 55 2, a plan view of the same; Fig. 3, a detail

view of one of the record-retaining shelves; Fig. 4, an edge view of the same; and, Fig. 5, a detail sketch of the mechanism for automatically locking the parts when not in use. 60

Similar numerals refer to similar parts throughout the several views.

The stationary base portion consists of an ornamental outer protective cabinet of any suitable design with a strong skeleton frame 65 secured therein in which the movable holding rack operates, and a suitable top or cover. This division of the stationary base into an outside cabinet, 1, and interior skeleton, 2, is in reality a detail of construction serving 70 herein to facilitate description and illustration, and it must be obvious that the skeleton may be an integral part of the cabinet itself in which the guides, bearings and parts providing for the motions of the rack, 3, may 75 be separately formed or placed instead of being fixed in their relative positions to a distinct framework as herein shown.

The movable rack, 3, resembles a rectilinear box and contains the record holders 80 or shelves, 4, and a drawer, 22, and is open at one side to afford access. It is adapted to telescope within the cabinet and be completely concealed therein by the cover, 5. This cover is hinged to the cabinet so that, when 85 opened forward, it may serve as a convenient table. As hereinafter described a talking machine or other similar instrument may be attached to this table, sufficient space being 90 allowed between the top of the rack 2, when down, and the cover 5 to permit of the suspension therein of such an instrument when the cover is closed.

The instrument itself is not a part of this 95 invention and is, therefore, not shown, but its position is indicated by dotted lines in Figs. 1 and 2, in which latter view is also shown my convenient method of readily securing the instrument.

The rack 3 is adapted to travel vertically 100 between the guide channels 7 secured to the frame 2 and which engage the guide strips 8 extending vertically along the two opposite sides of the rack. Near the top of the frame, 2, are two shafts 9, on each of 105 which are secured two powerful band spiral springs 10. Each of these four springs is positioned adjacent to an upper corner of the rack and has its outer terminal securely attached, at 11, to the corresponding bottom corner thereof, whereby the lowering of the 110 rack into the cabinet will serve to tighten

and constrict the spirals. To provide for the necessary adjustment of the spring-tension to the weight of the rack when loaded or partly so, a ratchet wheel 12 is secured 5 on each shaft 9 near a bearing and is engaged and controlled by an escapement pawl 13, pivoted to the frame 2 and provided with a lever 14 to be used as an operating handle and permit of the gradual reduction of the 10 spring-tension, a tooth at a time. Each shaft 9 is also formed with a relatively small flattened section 30 providing a square place to which a wrench for increasing tension may be applied. By this construction 15 the spring tension may be controlled at will and a proper counterpoise provided for the smooth and easy functioning of the rack.

Near the bottom of the rack, on opposite sides thereof and adjacent to each point 11 of spring attachment, is secured a tapered block or wedge 16, adapted to meet and come to rest against a similar, but inverted, wedge 17, one of which is fastened to the frame 2 adjacent to each spring 10. The 25 abutting surfaces of each pair of wedges are faced with sheet rubber, leather or other suitable material to soften the contact.

At the top of the rack 3 a keeper 19 is centrally positioned adapted, when the rack is 30 almost completely lowered, to thrust-out and pass behind a spring latch 20, attached to the frame 2, whereby the rack is locked in its normal position when not in use. This latch 20 has an extension passing, horizontally, through the front wall of the cabinet 1 (Fig. 5) and terminating in a suitable knob 21 to facilitate disengagement of said parts when it is desired to cause the rack 3 to ascend.

40 The shelves, which in my invention are also the record retainers, 4, are, preferably quite thin and, very strong and are retained by their opposite edges sliding and fitted within suitable narrow slots in the opposite walls of the rack 3, so as to be readily slid in and out, whereby, if required, different sized spacings between may be formed. A suitably shaped striplike spring ejector 23 is secured by pin and slot attachment 24 at each end of the spring, to the rear edge 45 of each shelf so that it curves forward centrally in the plane of a record 25 resting thereon, and acts to urge forward the record. A slender spring latch 26 is secured, preferably to the under side, to each shelf centrally and shaped so as to extend upwardly into the plane of the record thereon whereby the ejection of the latter by spring 23 is prevented. Each record 25 is thus secured 50 clamped in a safe method between the adaptable spring and the latch just described. When it is desired to release the record so retained, a slight downward pressure upon the outwardly extending end 27 55 of the latch is all that is necessary to result

in a forward movement of the record, directly into the hand. In inserting a record, this end 27 is held down, the record introduced and urged backward against the spring 23 which thereupon yields allowing 70 the record to be pushed in place, the latch is then released and permitted to rise and secure the record, as described.

The operation of my device is obviously simple. The table or cover 5 being thrown 75 forward forms a table. When an instrument is thereto attached this operation also brings it into playing position. The knob 21 is then pulled forward releasing the keeper 19 whereupon, under the action of 80 the springs 9, the rack 3 gently ascends until checked by the abutting of the rubber-faced blocks 16 and 17, when the cabinet is ready for use. One of the latches, 27, confining 85 the required record, is pressed and the record slips forward into the hand. After use the record is restored as already explained.

To restore the device to its condition of inactivity after use as described all that is 90 required is to reach up and place the fingers over the top of the rack, exert a gentle downward pull thereon and it will smoothly and easily yield and be readily lowered until caught by latch 20 and securely retained in the normal inclosed position. The table 5 and its attached instrument, if so employed, is then turned in, sealing the entire interior and forming an ornamental, 95 secure and dust-proof protector for both the 100 records and the instrument.

When the cover 5 is to be utilized as a table and holder for a talking machine or other musical instrument, it is provided with several parallel channels or recesses 105 partially faced with plates having key-hole shaped slots 28 adapted to retain the head end of threaded bolts 29. Such bolts inserted head-on into the circular end of said slots and slipped therealong so that the protruding threaded portion may be passed through holes bored through some under part of the instrument and then secured by 110 nuts, form the clamping means of retention of the instrument to the table.

When comparatively few records are stored in the rack, counterpoise may be auxiliated by placing suitable weighty objects in the drawer 22, although the intelligent use of the ratchet and escapement pawl will 115 be generally entirely efficient.

Having thus described a form of my invention I claim:

1. In a device of the character described the combination of an ornamental cabinet, 125 a vertically slidable music rack therein, horizontal shafts adjacent to the top of said rack and parallel to opposite sides thereof, spiral springs centered on said shafts and connected to said rack, means on said shafts 130

to alter and control the tension of said springs and means to alternately retain said rack depressed against the action of said springs and release said rack.

5. 2. In a device of the character described the combination of an ornamental cabinet, a vertically slidable music rack therein, horizontal shafts adjacent to the top of said rack and parallel to opposite sides thereof, 10 spiral springs centered on said shafts and connected to said rack, a ratchet wheel on each shaft, an escapement pawl engaged with each ratchet, a portion of each shaft formed to afford engagement with a wrench, 15 a keeper on said rack and a resilient latch to engage said keeper.

3. In a device of the character described the combination of an ornamental cabinet, a vertically slidable music rack therein, 20 horizontal shafts adjacent to the top of said rack and parallel to opposite sides thereof, spiral springs centered on said shafts and connected to said rack, continuous guideways substantially central of said shafts and perpendicular thereto, continuous guides on opposite sides of said rack engaged therein, means on said shafts to alter and control the 25 tension of said springs and means to alternately retain said rack against the action of 30 said springs and release said rack.

4. In a device of the character described the combination of an ornamental cabinet, a vertically slidable music rack therein, horizontal shafts adjacent to the top of said 35 rack and parallel to opposite sides thereof, spiral springs centered on said shafts and connected to said rack, continuous guideways substantially central of said shafts and perpendicular thereto, continuous guides on

opposite sides of said rack and engaged 40 therein, a ratchet wheel on each shaft, an escapement pawl engaged with each ratchet, a portion of each shaft formed to afford engagement with a wrench, a keeper on said rack and a resilient latch to engage said 45 keeper.

5. In a device of the character described the combination of an ornamental cabinet, a vertically resilient music rack appreciably shorter than said cabinet disposed therein, 50 a rotatable cover for said cabinet, means in said cover to secure and retain a musical instrument such as a phonograph, means to alter and control the degree of resiliency of said rack and means to alternately retain 55 and release said rack.

6. In a device of the character described, in combination with a stationary protective base, guiding means, a slidable rack guided thereby, actuating springs attached to said 60 base and so connected to said rack as to normally cause it to ascend, means to adjust the tension of said springs to properly counterpoise the weight of said rack, wedge shaped members on said base adjacent to 65 said springs, corresponding wedge shaped members positioned near the bottom corners of said rack and adapted, when said rack is elevated, to make contact with and be restrained by the first mentioned wedge-shaped members, each with each, a keeper on said rack, and a latch on said base adapted to engage with said keeper and retain said rack within said base. 70

JAMES E. BIRDSALL.
